UNITED STATES PATENT OFFICE.

DAVID L. LINDQUIST, OF YONKERS, NEW YORK, ASSIGNOR TO OTIS ELEVATOR COMPANY, OF NEW YORK, N. Y., A CORPORATION OF NEW JERSEY.

ELEVATOR.

1,206,448.

Specification of Letters Patent.

Patented Nov. 28, 1916.

Application filed June 20, 1913. Serial No. 774,746.

To all whom it may concern:

Be it known that I, DAVID L. LINDQUIST, a subject of the King of Sweden, residing in Yonkers, in the county of New York and 5 State of New York, have invented a new and useful Improvement in Elevators, of which the following is a specification.

My invention relates to elevators and more particularly to automatically controlled safety devices for elevators and has 10 for an object, the provision of a device for regulating the speed of an electric elevator.

Another object of the invention is the provision of a centrifugal device for slowing down and stopping an electric elevator 15 in the event of excessive speed.

A further object of the invention is the provision of means associated with the governor which controls the mechanical safety 20 clutch for preventing an elevator car from attaining too high a speed and to stop the latter in case a certain predetermined abnormal speed is reached.

Other objects of the invention will appear 25 hereinafter, the novel combinations of elements being pointed out in the annexed claims.

In the drawings, Figure 1 represents an 30 embodiment of my invention; Fig. 2 is an elevation view of the governor; Fig. 3 is a sectional plan view of Fig. 2; Fig. 4 is a diagrammatic view of the well known Ellithorpe safety device.

Like reference characters denote similar 35 parts in all of the figures.

Broadly speaking, the invention consists, among other things, in circuit controlling switches associated with the governor of 40 the mechanical safety device whose function is automatically to control the hoisting motor to cause the latter to reduce its speed in case the elevator car be traveling too fast in either direction and to prevent the car 45 from normally exceeding this speed, and further to stop the car in case of abnormal speed conditions, both of which operations take place before the governor operates the safety clutch.

Referring to Fig. 1, an elevator car C is 50 adapted to be raised or lowered by means of an electric motor M which is operatively connected therewith through the usual worm gearing contained in the gear case I.

An electric brake B co-acts with a brake 55 pulley which forms a coupling between the motor shaft and the worm shaft, and operates in the usual manner to stop and hold the motor from rotating when the current supply to the motor is cut off. The hoisting 60 motor is controlled from the car by means of a hand switch A which is adapted to close a circuit to the reversing switches R or R' and a fast speed switch F. A potential switch P is normally in closed circuit position as shown and connects the electrical 65 system with a suitable source of supply designated by + and -. An accelerating magnet D controls the starting resistance H and automatically and gradually brings 70 the motor up to speed each time the motor circuit is closed at one of the reversing switches. The fast and slow speed magnet F controls a resistance J in the shunt field of the motor, while a resistance K is also 75 connected in circuit with the shunt field and is controlled by the governor G in a manner to be pointed out hereinafter. Limit switches L and L are arranged in the 80 hatchway, and are adapted to be operated by a cam carried on the car when the latter reaches its normal limit of travel in either direction. A small switch E is located in the car, and is for the purpose of enabling the operator to stop the car at any point in 85 its travel in case of emergency. The safety clamp illustrated diagrammatically in Fig. 4 is merely typical and is here shown as the well known Ellithorpe safety device, and 90 comprises a pair of clamping jaws 2 and 3 which are adapted to engage the guide rails 8, 8, when the drum 4 is rotated to force outwardly the right and left threaded screws 5 and 6, respectively. The drum 4 is connected through a safety cable 7 to the governor cable 9, which in turn is connected to and driven by the elevator car through the yielding connection comprising the releasing carrier 10. The governor cable drives the centrifugal governor G located at the 95 top of the hatchway and is maintained under a tension by a weight 11 at the lower end of the hatchway. Associated with the 100 governor and operated thereby is a double set of cable clamps 12 and 13, which are 105 adapted to grasp the governor cable on both sides of the governor sheave 14, when the car exceeds a predetermined speed and thus

restrain the governor cable. When this action takes place the releasing carrier 10 lets go and the further movement of the car in either direction of travel results in unwinding the safety cable 7 from the drum 4, thereby rotating the latter to effect the actuation of the rail gripping clamping jaws 2 and 3 of Fig. 4 to stop the car.

The description thus far involves nothing new over the standard practice in elevator construction, but I propose to go farther by providing electric circuit controlling devices which are operated by the governor in accordance with the speed of the elevator to effect the control of the elevator and to effect the stop of the elevator by disconnecting the hoisting motor from the supply circuit and applying the brake in case the speed of the motor becomes excessively high. The governor is arranged to effect this automatic control of the motor before the car shall have reached a speed sufficient to enable the governor to operate the governor cable clamps 12 and 13 and apply the rail safety clamps.

Another feature of the invention is the provision of means associated with the governor clamps 12 and 13 whereby the latter will grasp the governor cable 9 with a yielding pressure so as to obviate all danger of breakage of the same in case the car should continue to move after the rail clamp safety has been fully applied and further to prevent a too powerful action of said rail clamp safety.

Since the governor and its associated mechanism form an important part of the invention, I will describe the same somewhat in detail.

Referring more particularly to Figs. 2 and 3, the sheave 14 is rotated by the governor cable 9 during the travel of the elevator car, and this sheave is connected through the usual bevel gearing to the fly balls 19, 19, which are adapted when subjected to centrifugal force to raise a lever 20 against the action of the governor spring 21 and one or more adjustable weights 22, 22. This lever 20 is connected through the rods 23, 23, to cranks 24 and 25, which are secured to shafts 26 and 27, respectively, adapted to rotate in brackets or supports 28, 28. Other shafts 29, 29, are also carried by the brackets 28, 28, and these shafts are adapted to have a bodily as well as a rotary movement with respect to the brackets 28, 28, owing to the slots 30, 30, in which the ends of these shafts are located. Each of the shafts 29, 26, 27 and 29, loosely carries a segmental gear such as 31 which is secured to or formed integral with a grooved periphery cable clamp 32, said gears being arranged in intermeshing pairs, and the corresponding clamps 32 being likewise arranged in pairs and adapted to wedge upon and clamp the governor cable 9 when the

said gears and clamps are rotated by the governor. Each clamp 32 of a pair of clamps is provided with an integral member such as 37, to which is secured a stop 36, normally engaged by a spring pressed latch 34 which prevents the rotation of the segmental gears and clamps 32. A cam 33 is secured to each of the shafts 26 and 27, and is adapted to be rotated by the governor in engagement with a co-acting cam such as 35 carried upon each of the latches 34 to effect the unlocking of the latches and permit the clamps to move by gravity into engagement with the opposite leads of the governor cable 9 to restrain the latter in its movement and thereby effect the operation of the rail clamp safety. In case gravity should fail to effect the operation of the governor clamps, a further movement of the cams 33, 33, carries them into engagement with the stops 36 and each of the members 37, 37, will be carried upwardly by the governor positively to actuate the cable clamps 32.

In order that the cable clamps may not wedge the governor cable too tightly and thereby make it possible to fracture or unduly strain the same when the rail clamps are applied I provide heavy compression springs 38, 38, which bear against the shafts 29, 29, and acting through the members 39, 39, force them toward one end of the slots 30, 30. It will readily be seen that the wedging action of the cable clamps upon the governor cable will tend to move said clamps away from each other and thereby further compress these springs, hence the latter serve as an efficient means to limit the grip of the clamps on the governor cable to a predetermined amount. While the movement of one set of clamps away from its co-acting clamp will tend to carry the corresponding segmental gears out of mesh with each other, the teeth of these gears are made of such length that a complete unmeshing can never take place under any conditions and the clamps will always move simultaneously.

The electrical features associated with the governor comprise a pair of cams 15 and 16 (see Figs. 1 and 3) which are secured to the shaft 27 and respond to every movement of the governor. A circuit controlling switch 17 is adapted to be closed by the cam 15 while another switch 18 with normally closed contacts is adapted to be opened by the cam 16, the switch 17 being arranged to operate before the switch 18, and both switches operate before the governor has reached a speed sufficient to actuate the rail clamp safety.

The operation of an electric elevator containing an embodiment of my invention may be seen from the following description of Fig. 1: Assuming the potential switch P is in closed position as shown, a self holding circuit for this switch is established from

the + main, contacts 40, wire 41, emergency switch E, limit switches L, L, in series, governor switch 18, magnet winding of the potential switch and to the — main. In order to operate the car, the lever of the car switch A is moved in one direction or the other, we will assume in a left hand direction, until it engages the switch contact 42. A circuit may now be traced through the magnet of the reversing switch R and the latter operates to close a circuit from the main line to the armature and field of the motor and the brake. A circuit is also closed to accelerating magnet D in parallel with the motor armature and this magnet automatically and gradually short circuits the starting resistance H by successively closing the contacts 44, 45, 46, and 47, in the order named in accordance with the varying counter electromotive force of the motor. The motor now operates at normal slow speed, the resistance K being in series with the shunt field winding, while the resistance J is short circuited by the contacts of the fast and slow speed magnet switch F. The operator next moves the car switch lever onto contact 43, thereby closing a circuit to the magnet winding of switch F, providing the entire starting resistance has first been short circuited and the contacts 48 in engagement with each other. Assuming such to be the case, the switch F operates to remove the short circuit around the resistance J and the latter is inserted in the shunt field winding of the motor and the motor at once assumes full normal speed with weakened field.

If for any reason the elevator should travel too fast, the governor will rotate the cam 15 to effect the closing of the switch 17. It will be observed that the contacts of this switch are connected in parallel to the resistances J and K, hence the closing of these contacts establishes a short circuit across both of these resistances and thereby substantially strengthening the motor field tending to effect a slow down of the motor. The conditions may be such that the motor does slow down, and if such is the case the governor will at once respond to said speed reduction and permit the switch 17 to open, and thereby reinsert the resistance K in the shunt field circuit tending to effect an increase in motor speed. Should the speed be increased, the governor will again operate to decrease it. From this it is seen that speed will be maintained substantially constant and cannot under normal conditions become excessive.

If, for some reason, the speed should become excessive the governor will rotate the cam 16 in position to open the switch 18, thereby open-circuiting the self holding magnet of the potential switch P and the latter drops its contacts, thereby opening the

motor circuit and applying the brake to stop the motor and hoist. Should the elevator further increase its speed due to some abnormal cause, the governor operates the clamps 12 and 13 to arrest the governor cable 9 and any further movement of the car pulls this cable loose from the car at the releasing carrier 10, and the safety drum is rotated to apply the rail clamps, with a pressure or retarding power which is predetermined but is always ample to stop the car with the heaviest load it will ever be called upon to carry.

The foregoing operations will take place regardless of the direction of car travel, since the direction of rotation of the governor sheave has no bearing on its operation, the element of speed being the predominating factor.

While I have shown and described a typical electric elevator system in which is used a shunt wound direct current hoisting motor, it is to be understood that my invention is equally well adapted to any and all elevator systems, whether the same use direct or alternating current or whether the motor be of other than a shunt machine, such for instance as a compound motor or an alternating current motor. Furthermore while I have shown a well known method of controlling the speed of a motor by varying its field strength, I propose in some cases to connect the governor switches to effect the control of the speed of the motor in any of the well known ways depending on conditions met in actual practice.

I desire not to be limited to the precise arrangement of parts herein disclosed since obviously those skilled in the art could readily make changes in the apparatus shown and described without departing from the spirit and scope of my invention.

What I claim and desire to secure by Letters Patent of the United States is:—

1. In an elevator, the combination of a car, guide rails therefor, a brake carried by the car adapted to co-act with said guide rails, a governor for controlling said brake, an electric hoisting motor, a source of current supply, branch circuits leading from a source of supply to the armature and field circuits, a switch in each of said branch circuits, a resistance in parallel to one of said switches, and a plurality of cams controlled by the governor arranged to effect the successive operation of said switches to slow down and stop the motor.

2. The combination with an elevator car, a safety device carried by the car, a running rope associated with said device, a speed governor, a clamp adapted to grip said running rope to effect the operation of the safety device, a latch normally preventing the operation of said clamp, and means operated by the governor for releasing said

latch and moving said clamp into gripping engagement with the running rope.

3. The combination with an elevator car, a safety device, carried by the car, a running rope associated with said device, a speed governor, a clamp adapted to grip said running rope to effect the operation of the safety device, a spring pressed latch normally holding said clamp against operation, and a dog actuated by the governor first to release said latch and thereafter move said clamp into engagement with the running rope.

4. In an elevator, the combination with a hoisting motor, car and guide rails, of a safety device adapted to clamp the car to the guide rails, a governor, a running rope associated with the governor and safety device, a shaft controlled by the governor, an eccentric clamping member on said shaft adapted to engage the running rope and thereby actuate the safety device, a cam on said shaft, and a switch controlling a circuit to said motor operated by said cam.

5. In an elevator, the combination with a hoisting motor, car and guide rails, of a safety device adapted to clamp the car to the guide rails, a governor, a running rope associated with the governor and safety device, a shaft controlled by the governor, an

eccentric clamping member on said shaft adapted to engage the running rope and thereby actuate the safety device, a pair of cams on said shaft, a separate switch operated by each cam, and circuits controlling the slowing down and stopping of said motor controlled by said switches.

6. In an elevator, the combination with a hoisting motor, car and guide rails, of a safety device adapted to clamp the car to the rails, a governor, a running rope associated with the governor, car and safety device, a clamp adapted to engage said running rope to effect the operation of the safety device, a switch for controlling the speed of the motor, an additional switch for stopping the motor, and an operative connection between the governor and both switches for effecting first the successive operation of the switches to slow down and stop the motor and thereafter operate the said clamp to effect the operation of the safety device.

In testimony whereof, I have signed my name to this specification in the presence of two subscribing witnesses.

DAVID L. LINDQUIST.
